UNITED STATES PATENT OFFICE.

HARRY J. NICHOLS, OF WASHINGTON, DISTRICT OF COLUMBIA.

WATER-IMPACT FUSE.

Application filed November 18, 1919. Serial No. 338,954.

To all whom it may concern:

Be it known that I, HARRY J. NICHOLS, a citizen of the United States, residing at Washington, District of Columbia, have invented new and useful Improvements in Water-Impact Fuses, of which the following is a specification.

My invention relates to improvements in fuses for shells, and it is intended to provide a fuse which is simple in construction, safe against accidents and efficient in operation. It is particularly intended to operate instantly and without fail when the shell strikes the water, this being desirable with certain special classes of projectiles.

Percussion fuses of the usual type which operate when the shell is suddenly arrested in its flight do not operate reliably on water impact and particularly when the shell ricochets, and in any case not until the shell has penetrated into the water, which is not always desirable. My invention, on the contrary, operates when the point of the projectile only has penetrated the water a very short distance and whether or not the shell ricochets without arresting its flight to any considerable degree.

My invention will be understood by reference to the accompanying drawings in which the same parts are indicated by the same numbers throughout the several views.

Figure 1 shows a section through the fuse stock, with parts shown in elevation and in the safety position.

Figure 2 is a central longitudinal section, the parts being shown in elevation and in the firing position.

Figures 3 and 4 are detail sections of two interfitting parts.

Referring to the drawing in detail, 5 is a fuse-stock, which may be screwed into the nose of a projectile in the usual way. The fuse-stock is bored out to form the chamber 6 in which a cylindrical sleeve 7 slides. The forward portion of the fuse-stock is screw-threaded as at 8 to receive a fuse nose-plug 10 provided with an axial duct or vent 11 as shown, though the fuse nose-plug may be made an integral part of the fuse-stock if so desired. In similar manner the rearward portion of the bore of the fuse-stock is screw-threaded as at 12 to receive a fuse base plug 13 which is provided with an axial priming vent 14.

The cylindrical sleeve 7 before mentioned is bored out to provide a cylindrical cham-

ber 15 concentric to its exterior and containing a firing plunger 16. The chamber 15 is closed at the front except for a circular hole 17 slightly larger and opposite the vent 11 in the fuse nose-plug and formed by an internal flange 19 in the sleeve 7. At the rear a slight recess is provided into which a primer container 18 is screwed or otherwise secured as desired.

A primer 20 is held in a recess in the primer container by a primer support 21 provided with a primer vent 22 and secured in the recess by a screw joint or other suitable means. The rear portion of the bore of the primer container is enlarged in diameter so as to form a powder chamber for the ignition charge, and is provided with lips to hold an igniter disc 29 in place in front of the powder.

The primer container 18 has a plurality of cuts in its periphery, as shown in Figure 4, leaving an interrupted thread and two or more longitudinal channels 24 between the primer container and the sleeve 7 (three being shown in present embodiment of my invention).

The wall of the plunger 16 is cut away in alternate sections corresponding to the lands of the primer container periphery, leaving two or more legs 25, Figure 3, (three being shown) which extend through and slide in the channels 24. A firing pin 26 is screwed into the front part of the plunger 16, extending inwardly with the point opposite the primer 20. The exterior face of the plunger 16 is formed into a cupped annular groove with a conical boss 27 at the center and a lip 28 at the periphery. This lip acts as an obturator to prevent the leakage of liquid past the plunger.

Between the plunger 16 and the member 18 is a helical spring 30 mounted under compression. This spring need not be of any great strength, but simply is to insure that the plunger 16 remains in the forward position against the flange of the sleeve 7.

Another helical spring 31 is mounted under compression between the fuse nose-plug 10 and the sleeve 7. This spring likewise need not be of any great strength, but should have sufficient force to sustain the sleeve and the plunger at the rear of the chamber 6 in the fuse stock. This is a precautionary measure, as will be hereinafter described.

The operation of the device is as follows. The parts would normally be in the position

shown in Figure 1, and would continue in that position when the gun is fired and while the shell is in flight. The legs 25 of the plunger 16 rest against the fuse base-plug 13, thus preventing the firing pin 26 from coming into contact with the primer 20. When the shell strikes the water, however, the slight arresting of the shell's flight on impact tends to throw both the sleeve 7 and the plunger 16 forward. Before this action is completed, however, water moving with great velocity, due to the relative velocity of the shell and the body of water which it strikes, enters the interior of the fuse 15 through the vent 11 in a jet and impinges against the plunger 16, forcing it to the rear. After impinging on the plunger 16 the entering jet of water is deflected by the cupped groove and lip 28 on the face of the plunger 16 and strikes the rear face of the flange 19 of the sleeve 7, driving it forward. It will thus be seen that the kinetic energy of the entering jet of water is utilized to bring the primer 20 and the firing pin 26 together 20 instantly and with great force, exploding the primer and setting fire to the igniter charge 23.

The firing of the primer, therefore, depends on a relative movement of the plunger 16 and the sleeve 7. This relative movement cannot be produced by accident, as will be apparent when it is considered that if the shell is dropped on its nose the plunger and the sleeve will be impelled forward together 30 and will be cushioned and returned to their normal position without relative movement by the spring. If the shell is dropped on its base, the legs of the plunger prevent relative movement and if the shell drops on its side, 35 there is no unrestrained force operating to produce relative movement. Were the spring 31 not provided, however, and should the sleeve 7 stick in its forward position due to corrosion or binding, a drop on the base, or 40 firing in the gun, might fire the primer. The spring 30 is provided to insure that the sleeve and plunger will always move together.

On striking the water, the sleeve 7 is thrown forward, its weight supplementing the reaction of the jet of entering water, while the plunger 16 which must be checked and prevented from going forward is small and light in weight, as well as being acted 50 upon directly by the entering water. The operation occurs when the shell has penetrated into the water only a few inches, and is consequently unaffected by ricochet and does not depend on arresting the flight of 55 the shell.

It will thus be seen that I have provided a fuse which is entirely safe, extremely rapid in action, and which is well adapted to the purposes for which intended.

60 While the accompanying drawings illus-

trate what I believe to be the preferred embodiment of my invention, it is to be understood that the invention is not limited thereto, but that various changes may be made in the construction, arrangements and proportions of the parts without departing from the scope of the invention as defined in the appended claims.

70 What I claim is:

75 1. In a fuse, in combination, a plunger, a sleeve, a firing pin carried by one and a primer by the other, said plunger and sleeve both being adapted to have movement through the impingement of a jet of liquid upon said plunger and sleeve.

80 2. In a fuse of the character described, in combination, a fuse stock having an opening at the forward end, a plunger, a sleeve surrounding said plunger, a firing pin and a primer carried by said plunger and sleeve, said sleeve and plunger both being adapted to have relative movement with respect to the stock when engaged by a jet of water entering through the opening in the stock whereby the firing pin and primer are 85 brought forcibly into contact.

90 3. In a fuse of the character described, in combination, a fuse stock having an opening for the admission of water, a plunger therein, a movable sleeve surrounding the plunger, a firing pin and primer carried by said sleeve and plunger and means for deflecting a jet of liquid passing in through the opening of the stock from the plunger against the sleeve thereby to secure relative movement of both of said parts and bring the firing pin and detonator into engagement.

95 4. In a fuse of the character described, in combination, a fuse stock having a water inlet opening, a plunger, a movable sleeve 100 surrounding said plunger, a firing pin and primer carried by the sleeve and plunger and means comprising an annular groove in the face of the plunger for deflecting a jet of water entering through the inlet opening 105 against said sleeve thereby to secure movement of said sleeve to bring the firing pin and primer into engagement.

110 5. In a fuse of the character described, in combination, a fuse stock provided with a longitudinal duct communicating with the exterior of the fuse stock, a plunger provided with a firing pin mounted therein and having a plurality of longitudinal extensions, a sleeve carrying a primer enclosing said plunger and provided with longitudinal channels in which the longitudinal extensions of said plunger are free to slide, and means for deflecting a jet of liquid entering through the duct of the fuse stock 115 from the plunger to the sleeve to secure movement of the same.

120 6. In a fuse of the character described, in combination, a fuse stock provided with a longitudinal duct communicating with the 125

- exterior of the fuse stock, a plunger provided with a firing pin mounted therein and having a plurality of longitudinal extensions, a sleeve carrying a primer enclosing 5 said plunger and provided with longitudinal channels in which the longitudinal extensions of said plunger are free to slide, and means for deflecting a jet of liquid entering through the duct of the fuse stock 10 from the plunger to the sleeve to secure movement of the same, said means comprising an annular cupped groove in the fact of the plunger, and a lip at the periphery of the groove.
- 15 7. In a fuse of the character described, in combination, a fuse stock, a fuse stock plug provided with a longitudinal duct communicating with the exterior of the fuse stock, a plunger provided with a firing pin mounted 20 therein, and provided with a plurality of longitudinal extensions, a sleeve carrying a primer-container with primer mounted therein, said primer-container being provided at its periphery with longitudinal 25 grooves in which the longitudinal extensions of the plunger extend and are free to slide, and means for deflecting a jet of water entering through the longitudinal duct in the fuse nose-plug from the plunger to the sleeve 30 to secure movement of the same.
8. In a fuse, in combination, a fuse stock, a plunger, a movable sleeve enclosing said plunger, a firing pin and a primer carried by said plunger and sleeve, a spring interposed 35 between said plunger and sleeve and a spring interposed between the fuse stock and the sleeve.
9. In a fuse, in combination, a fuse stock provided with a water inlet, a firing pin, a primer, and means for utilizing the kinetic 40 energy of a jet of water entering said inlet on impact to bring said firing pin and primer into forcible contact, said means comprising a plunger and a sleeve movable 45 with respect to both the fuse stock and the plunger.
10. In a fuse, in combination, a fuse stock, a fuse nose-plug, a plunger, a sleeve carrying a primer container with a primer mounted 50 therein, a spring mounted between said plunger and sleeve, and a spring mounted between the fuse nose-plug and the sleeve.
11. In a fuse, in combination, a fuse stock provided with a water inlet, a firing pin, a primer, and means operable by the energy 55 of reaction of a jet of water entering said inlet on impact to bring said primer into forcible contact with said firing pin, said means comprising a movable sleeve carrying the primer. 60
12. In a fuse, in combination, a fuse stock provided with a water inlet, a firing pin, a primer, and means operable by the kinetic energy of a jet of water entering said inlet to arm said firing pin and fire said 65 primer.
13. In a fuse, in combination, a fuse stock provided with a water inlet, a firing pin, a primer and means operable by the kinetic energy of a jet of water entering said inlet 70 to arm said firing pin and fire said primer, said means comprising a plunger and a movable sleeve.
14. In a fuse, in combination, a fuse stock provided with a water inlet, a firing pin, a primer, and means for utilizing the kinetic energy of a jet of water entering said inlet upon impact to arm the fuse and bring the firing pin and primer into engagement. 75
15. In a fuse, in combination, a fuse stock provided with a water inlet, a firing pin, a primer, and means operable by the impingement of a jet of water entering said inlet upon impact to bring said primer and firing pin into engagement, said means comprising 80 a plunger and a movable sleeve.
16. In a fuse, in combination, a fuse stock provided with a water inlet, a firing pin, a primer, a movable member, and means whereby the impulse force of water entering said inlet on impact is utilized as the sole means of arming said firing pin and firing said primer. 90
17. In a fuse, in combination, a fuse stock provided with a water inlet, a firing pin, a primer, and means whereby the impulse force of water entering said inlet on impact is utilized as the sole means of arming said firing pin and firing said primer. 95
18. In a fuse, in combination, a fuse stock provided with a water inlet, a member carrying a firing pin, and a member carrying a primer and means whereby the impulse force of water entering said inlet on impact is utilized as the sole means of bringing said 100 members into operative relation to arm said firing pin and fire said primer.

Signed at Washington, District of Columbia, this 31st day of October, 1919.
HARRY J. NICHOLS.
